The ornamental design for a conversion fitting, as shown and described.

DESCRIPTION

FIG. 1 is a front view of a conversion fitting, with a top view and a bottom view being identical thereto and with a rear view being a mirror image thereof;

FIG. 2 is a left side view of the conversion fitting;

FIG. 3 is a right side view of the conversion fitting;

FIG. 4 is a front cross-sectional view of the conversion fitting; and,

FIG. 5 is an enlarged, partial cross-sectional view of the conversion fitting showing the circled portion in FIG. 4. The dot dash dot broken lines denote the boundaries of the detail areas in the conversion fitting and form no part of the claimed design.
